W. H. MARTIN.

INSULATOR.

APPLICATION FILED MAR. 14, 1912.

1,070,151.

Patented Aug. 12, 1913.

UNITED STATES PATENT OFFICE.

WILLIAM H. MARTIN, OF UKIAH, CALIFORNIA, ASSIGNOR OF ONE-HALF TO DAISY NEWMAN, OF UKIAH, CALIFORNIA, AND ONE-HALF TO MARTIN P. KNUPP, OF YOUNTSVILLE, CALIFORNIA.

INSULATOR.

Specification of Letters Patent.

Patented Aug. 12, 1913.

1,070,151.

Application filed March 14, 1912. Serial No. 683,751.

To all whom it may concern:

Be it known that I, WILLIAM H. MARTIN, residing at Ukiah, in the county of Mendocino and State of California, have invented 5 a new and Improved Insulator, of which the following is a specification.

This invention is in the nature of an improved glass insulator for telephone and telegraph service, and it consists in the peculiar construction and arrangement of parts 10 hereinafter fully explained, specifically pointed out in the appended claims and illustrated in the accompanying drawings, in which:

15 Figure 1, is a perspective view of a portion of a pole, and a cross arm with my improved construction of insulator applied to the said cross arm. Fig. 2, is a longitudinal section of the insulator taken substantially 20 on the line 2—2 on Fig. 1. Fig. 3, is a transverse section thereof on the line 3—3 on Fig. 2. Fig. 4, is a perspective view of the several parts that constitute my improved insulator separated from each other.

25 In its practical arrangement my improved insulator comprises two wire clamping members having opposing corrugated surfaces, the upper one having convexed portions 10 for seating in the concaved depressions 20 in the lower member 2. The clamping members 1 and 2 are of glass or other analogous material, and the lower member has pendent flanges 21 that lap over the opposite edge of the cross arm 3 for assisting in keeping the 35 members 1 and 2 in place and for preventing water from getting under the glass member 2. By corrugating the opposing faces of the members 1 and 2 they mesh with each other and serve to positively crimp the wire 40 between them, and thereby firmly clamp the said wire.

4 designs a sheet metal cover or housing that fits over the top insulating member 1, the latter having a rounded upper face, 45 as shown. The ends of the housing are bent at right angles to form foot flanges 40 through which pass clamp bolts 5 that extend through the cross bar and are made fast by the thumb nuts 50.

50 7 designates a packing of fibrous material

between the housing 4 and the top of the member 1 and which consists in holding down the member 1 under ordinary expansion of the housing 4.

From the foregoing taken in connection 55 with the drawing, the complete construction, and advantages of my invention will be readily understood.

What I claim is:

1. In combination with a support, an insulator comprising a vitreous body formed of an upper and a lower section, the opposing faces of which have intermeshing portions whereby to grip and crimp a wire 60 therebetween, the lower section having pendent flanges for lapping the opposite edges of the support, a sheet metal covering on the vitreous body having end flanges for 65 engaging the support, and means for securing the flanges on the support. 70

2. In combination with a support, an insulator comprising a vitreous body formed of an upper and a lower section, the opposing faces of which have intermeshing portions whereby to grip and crimp a wire 75 therebetween, the lower section having pendent flanges for lapping the opposite edges of the support, a sheet metal covering on the vitreous body having end flanges for 80 engaging the support, means for securing the flanges on the support, and a fibrous lining between the covering and the vitreous body.

3. In combination with a supporting arm; 85 an insulator comprising an upper and a lower section of vitreous material, the opposing faces of the said section having intermeshing corrugations whereby to crimp the wire that is held between said faces, the lower section having pendent flanges for 90 lapsing over the opposite edges of the supporting arm, a sheet metal cover for the insulator sections, said cover having apertured flanges for seating on the support, bolt and nut devices for securing the said flanges 95 on the supporting arm, and a fibrous lining between the vitreous body and the cover.

WILLIAM H. MARTIN.
